DISPENSING CLOSURE

Ralph B. Waite and Sheridan C. Waite, Springville, N. Y.; said Ralph B. Waite assignor to said Sheridan C. Waite

Application May 13, 1935, Serial No. 21,256

15 Claims. (Cl. 221—60)

This invention relates to certain new and useful improvements in dispensing closures.

The primary object of the invention is to provide a dispensing closure or receptacle wherein the closure member including a cap and slide valve structure carried thereby is adapted to be engaged with a normally closed or sealed receptacle with the valve device constructed and arranged for breaking or severing the seal to the receptacle and to regulate the discharge of the contents of the receptacle therethrough.

A further object of the invention is to provide a dispensing closure of the foregoing character and of the type especially designed with a collapsible tube for the dispensing of toothpaste, creams and like materials with a tubular valve device slidably carried by an enclosing cap adapted for threaded engagement with the neck of the collapsible tube with a spur or cutter finger carried by the inner end of the valve device adapted to be moved by the cap into piercing engagement with a seal or closure in the tube neck with the valve device thereafter rotated to cut an opening in the collapsible tube closure and through which opening the valve device is slidably movable by threaded movement of the cap onto the tube neck.

A still further object of the invention is to provide a dispensing closure of the foregoing character with the tubular valve having limited sliding movement in the cap within the range of a cooperating shoulder and abutment ring on the cap and tubular valve respectively with the tubular valve limited in its inward movement by engagement by the abutment ring with the outer end of the neck of the shoe.

With the above and other objects in view that will become apparent as the nature of the invention is better understood, the same consists in the novel form, combination and arrangement of parts hereinafter more fully described, shown in the accompanying drawing and claimed.

In the drawing:—

Figure 1 is a fragmentary longitudinal sectional view of a collapsible tube and cap with the valve device carried by the cap illustrated in elevation and showing the cap partially threaded onto the neck of the tube with the closure disk for the tube at the outer end of the tube neck;

Figure 2 is a fragmentary longitudinal sectional view, similar to Figure 1, showing the tube cap fully screwed home and a circular opening cut in the tube closure by the valve device carried by the cap;

Figure 3 is an enlarged fragmentary longitudi-

nal sectional view of the valve device with the valve device having an abutment ring frictionally engaged with the outer end of the tube neck;

Figure 4 is a fragmentary longitudinal sectional view of another form of the invention wherein a tapered portion of the abutment ring on the valve device engages a tapered seat in the neck of the tube; and

Figure 5 is a fragmentary sectional view of another form of invention wherein the valve device embodies a spiral or screw portion to form an opening in the closure disk of the tube.

While the dispensing closure may be associated with receptacles of various types for the dispensing of different substances, the same is herein shown for purposes of illustration as associated with a collapsible tube 10 of the type usually employed as a container for paste, creams and the like and in which the tube embodies a shoulder 11 carrying an externally threaded neck 12. The collapsible tube 10 is normally sealed at the neck portion thereof by a closure disk 13 preferably arranged adjacent the outer end of the neck, although this closure disk 13 may be positioned at any point desired relative to the length of the neck.

The dispensing closure embodies a tubular cap having a tapered upper end 14 and a cylindrical lower end 15 that is internally threaded for engagement with the threaded neck 12 of the collapsible tube 10. The inner face of the tubular cap is provided with an annular channel 16 terminating at one end at the adjacent end of the threaded portion of the cap while the other end of the annular channel is spaced from the outer end of the cap and defines an annular shoulder 17, and a tapering pocket 17a.

A tubular valve device is carried by the cap and includes a tubular stem 18 that is closed at its outer end with the inner end thereof open and tapered as at 19 with a cutting finger 20 projecting beyond the tapered end 19 and in the plane thereof. The outer end of the tubular stem 18 frictionally moves in contact with the inner cylindrical wall 21 in the outer end of the cap outwardly of the annular channel 16 and an annular abutment ring 22 is carried by the tubular valve stem 18 intermediate its ends for frictional sliding engagement with the wall of the channel 16. As shown more clearly in Figure 3, the upper edge of the abutment ring 22 is slightly rounded as at 23 and merges into a tapered portion 23a that is received in the tapering pocket 17a. The

lower edge of the abutment ring 22 is of right angular formation to provide a shoulder 24, and a tapering annular shoulder 25 is formed on the tubular valve stem 18 in juxtaposition to the abutment ring 22. A lateral port 26 is provided in the tubular valve stem 18 adjacent its outer end for the lateral discharge of contents of the collapsible tube 10 through the tubular valve stem.

The tubular cap is first placed in threaded engagement with the neck 12 of the collapsible tube 10 as shown in Figure 1 and the tubular cap is then further threaded onto the tube neck to cause the cutting finger 20 to pierce the neck closure 13. The valve stem 18 may then be rotated to cut a circular opening in the disk 13 which is turned back as at 13a and shown in Figure 2. Threaded movement of the tubular cap onto the neck 12 of the collapsible tube continues until the abutment shoulder 27 at the inner end of the annular channel 16 moves into engagement with the outer end of the neck 12 as shown in Figures 2 and 3, and during this movement, the inner end of the tubular stem 18 moves through the opening formed in the closure disk 13 and in frictional engagement with the annular rib 12a that remains in the tube neck when the closure disk 13 is cut away. The cutting of the closure disk 13 may also be accomplished by the rotation of the tubular cap in threaded engagement with the neck 12, the tubular stem 18 being wedgingly engaged with the cap by the engaging faces 23-17 and 23a-17a and forced downwardly through the neck 12 by the shoulder 17 at the upper end of the annular channel 16 being engaged with the abutment ring 22 of the tubular stem.

With the tubular stem 18 in the position shown in Figure 3, the lateral discharge port 26 thereof is closed by the outer end of the tubular cap and the tapered shoulder 25 on the tubular stem 18 bindingly engages the upper end of the neck 12 to secure a tight engagement for retaining the tubular stem in its retracted position against accidental projection thereof. When it is desired to dispense the contents of the collapsible tube 10, the outer knurled end 18a of the tubular stem is gripped by the user and the tubular stem is withdrawn outwardly of the cap to the position shown in Figure 2, with the lateral discharge port 26 disposed outwardly of the cap while the inner end of the tubular stem frictionally rides on the bead 12a that remains when the closure disk 13 is cut away. The bead 12a acts to prevent passage of the paste, cream or like contents of the tube into the annular channel 16 and to direct the tube content into the inner open end of the tubular stem 18 for discharge through the lateral port 26. In the event that the contents of the collapsible tube pass between the rib 12a and tubular stem into the annular channel, the abutment ring 22 wipes the wall of the channel, the shoulder 24 of the abutment ring acting to return any material therein to the collapsible tube while the rounded upper end of the ring 22 permits any of the material that may have passed upwardly through the annular channel above the ring to escape downwardly when the ring is moved into engagement with the abutment shoulder 17 as shown in Figure 2, and such material thereafter returned by the shoulder 24 to the collapsible tube.

In the form of the invention illustrated in Figure 4, the tubular stem 18 of the valve stem carries an abutment ring 22a and a tapered shoulder 25a. The neck 12 of the collapsible tube 10 as shown in Figure 4, has a closure disk 13 with a part thereof cut away as at 13a and the inner

side of the upper end of the neck 12 is provided with a tapering or conical seat 30 to receive the tapered shoulder 25a on the tubular stem 18, this arrangement providing a tight fit between the tubular stem 18 and neck 12 of the collapsible tube to prevent the escape of contents of the tube, and to secure the stem 18 in closed position against accidental movement.

In the form of invention illustrated in Figure 5, the collapsible tube 31 carries a tubular neck 32 in which a tubular valve plug 33 is slidably mounted and said neck 32 at the lower end thereof carries a closure disk for the tube that is adapted to be cut away as at 34 by means of the cutter finger 35 at the lower end of the threaded portion 36 of the tubular stem 33. The stem 33 and screw portion 36 are of tubular formation and the stem has a lateral port 37 that is normally closed by the neck 32 and adapted to be exposed by gripping the handle or head 38 of the tubular stem 33 to withdraw the latter and position the lateral port 37 outwardly of the outer end of the neck 32. A wedging interfitting connection is established between the outer end of the neck 32 and head 38 of the tubular stem 33 to retain the latter in the tubular neck against accidental displacement.

From the above detailed description of the invention, it is believed that the construction and operation thereof will at once be apparent and while there is herein shown and described the preferred embodiment of the invention, it is nevertheless to be understood that minor changes may be made therein without departing from the spirit and scope of the invention as claimed.

We claim:

1. In a dispensing closure, a container having a neck, a closure disk in the neck, a tubular cap axially movable on the neck, a dispensing valved tube slidable in the cap and projecting through the outer end thereof, means carried by the tube and cooperating with the cap and neck for limiting sliding movements of the tube relative to the cap, a cutting finger on the inner end of the valved tube and said cap adapted to move the tube when the latter is at its limit of outward movement relative to the cap for moving the cutting finger into severing engagement with the closure disk.

2. In a dispensing closure, a container having a neck, a closure disk in the neck, a tubular cap axially movable on the neck, a dispensing valved tube slidable in the cap and projecting through the outer end thereof, means carried by the tube and cooperating with the cap and neck for limiting sliding movements of the tube relative to the cap, a cutting finger on the inner end of the valved tube and said cap adapted to move the tube when the latter is at its limit of outward movement relative to the cap for moving the cutting finger into severing engagement with the closure disk, the inner end of the valved tube being confined by the cap within the cut-out portion of the closure disk and frictionally engaged with the wall of the cut-out portion when the cap is screwed home.

3. In a dispensing closure, a container having a neck, a closure disk in the neck, a tubular cap axially movable on the neck, a dispensing valved tube slidable in the cap and projecting through the outer end thereof, a cutting finger on the inner end of the valved tube and said cap adapted to move the tube when the latter is at its limit of outward movement relative to the cap for moving the cutting finger into severing engagement with the closure disk, an annular abut-

- 5 4. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapted
35 to move the tube when the latter is at its limit
40 of outward movement relative to the cap for
45 moving the cutting finger into severing engage-
50 ment with the closure disk, the inner end of the
55 valved tube being confined by the cap within
60 the cut-out portion of the closure disk and friction-
65 ally engaged with the wall of the cut-out
70 portion when the cap is screwed home, an annular
75 abutment on the valved tube, an annular abutment
80 on the cap and said tube abutment co-
85 operating with the cap abutment and end of the
90 neck for limiting sliding movements of the
95 valved tube relative to the cap.
- 5 5. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapted
35 to move the tube when the latter is at its limit
40 of outward movement relative to the cap for mov-
45 ing the cutting finger into severing engagement
50 with the closure disk, the inner end of the valved
55 tube being confined by the cap within the cut-out
60 portion of the closure disk and frictionally en-
65 gaged with the wall of the cut-out portion when
70 the cap is screwed home, the cap having an an-
75 nular channel therein with an abutment shoul-
80 der at its outer end facing the outer end of the
85 tube neck and an abutment ring on the valved
90 tube adapted for engagement with the abutment
95 shoulder and neck for limiting movements of the
valved tube.
- 5 6. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engage-
50 ment with the closure disk, the inner end of the
55 valved tube being confined by the cap within
60 the cut-out portion of the closure disk and friction-
65 ally engaged with the wall of the cut-out portion
70 when the cap is screwed home, an annular abutment
75 on the valved tube, an annular abutment
80 on the cap and said tube abutment co-
85 operating with the cap abutment and end of the
90 neck for limiting sliding movements of the
95 valved tube relative to the cap, and said valved tube
having a lateral port adjacent its outer end normally
closed by the cap when the valved tube is re-
tracted and exposed for lateral discharge when
the valved tube is projected.
- 5 7. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engagement
50 with the closure disk, the inner end of the valved
55 tube being confined by the cap within the cut-out
60 portion of the closure disk and frictionally en-
65 gaged with the wall of the cut-out portion when
70 the cap is screwed home, the cap having an an-
75 nular channel therein with an abutment shoul-
80 der at its outer end facing the outer end of the tube
85 neck and an abutment ring on the valved tube adapt-
90 ed for engagement with the abutment shoulder and
95 neck for limiting sliding movements of the valved
tube.
- 5 8. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engagement
50 with the closure disk, the inner end of the valved
55 tube being confined by the cap within the cut-out
60 portion of the closure disk and frictionally en-
65 gaged with the wall of the cut-out portion when
70 the cap is screwed home, the cap having an an-
75 nular channel therein with an abutment shoul-
80 der at its outer end facing the outer end of the tube
85 neck and an abutment ring on the valved tube adapt-
90 ed for engagement with the abutment shoulder and
95 neck for limiting sliding movements of the valved
tube.
- 5 9. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engagement
50 with the closure disk, the cap having an annular
55 channel therein with an abutment shoulder at its
60 outer end facing the outer end of the tube neck
65 and an abutment ring on the valved tube adapt-
70 ed for engagement with the abutment shoulder and
75 neck for limiting outward movement of the
valved tube, and a conical shoulder on the
valved tube beneath the abutment ring adapt-
ed to be moved into binding engagement with the
upper end of the neck to prevent accidental pro-
jection of the valved tube.
- 5 10. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engagement
50 with the closure disk, the inner end of the valved
55 tube being confined by the cap within the cut-out
60 portion of the closure disk and frictionally en-
65 gaged with the wall of the cut-out portion when
70 the cap is screwed home, the cap having an an-
75 nular channel therein with an abutment shoul-
80 der at its outer end facing the outer end of the tube
85 neck and an abutment ring on the valved tube adapt-
90 ed for engagement with the abutment shoulder and
95 neck for limiting outward movement of the valved
tube, and a conical shoulder on the valved tube beneath
the abutment ring adapt-
ed to be moved into binding engagement with the
upper end of the neck to prevent accidental pro-
jection of the valved tube.
- 5 11. In a dispensing closure, a container having
10 a neck, a closure disk in the neck, a tubular cap
15 axially movable on the neck, a dispensing valved
20 tube slideable in the cap and projecting through
25 the outer end thereof, a cutting finger on the
30 inner end of the valved tube and said cap adapt-
35 ed to move the tube when the latter is at its limit
40 of outward movement relative to the cap for mov-
45 ing the cutting finger into severing engagement
50 with the closure disk, the cap having an annular
55 channel therein with an abutment shoulder at its
60 outer end facing the outer end of the tube neck
65 and an abutment ring on the valved tube adapt-
70 ed for engagement with the abutment shoulder and
75 neck for limiting outward movement of the
valved tube, and a conical shoulder on the
valved tube beneath the abutment ring adapt-
ed to be moved into binding engagement with the
upper end of the neck to prevent accidental pro-
jection of the valved tube.

- the outer end thereof, a cutting finger on the inner end of the valved tube and said cap adapted to move the tube when the latter is at its limit of outward movement relative to the cap for moving the cutting finger into severing engagement with the closure disk, the cap having an annular channel therein with an abutment shoulder at its outer end facing the outer end of the tube neck and an abutment ring on the valved tube adapted for engagement with the abutment shoulder and neck for limiting sliding outward movement of the valved tube, a conical shoulder on the valved tube beneath the abutment ring and a conical seat at the outer end of the neck adapted to be bindingly engaged by the conical shoulder to prevent accidental projection of the valved tube.
12. In a dispensing closure, a container having a neck, a closure disk in the neck, a dispensing valved tube slidably mounted in the neck, the inner end of the tube being threaded and a cutting finger at the inner end of the threaded portion, the threaded end and cutting finger being adapted to cut an opening in the closure disk and thread the valved tube inwardly through the closure disk opening.
13. In a dispensing closure, a container having a neck, a closure disk in the neck, a dispensing valved tube slidably mounted in the neck, the inner end of the tube being threaded and a cutting finger at the inner end of the threaded portion, the threaded end and cutting finger being adapted to cut an opening in the closure disk and thread the valved tube inwardly through the closure disk opening.
14. In a dispensing closure, a container having a neck, a closure disk in the neck, a dispensing valved tube slidably mounted in the neck, the inner end of the tube being threaded and a cutting finger at the inner end of the threaded portion, the threaded end and cutting finger being adapted to cut an opening in the closure disk and thread the valved tube inwardly through the closure disk opening.
15. In a dispensing closure, a container having a walled discharge end, a closure disk therein, a dispensing valved tube having a cutting finger at its inner end slidably mounted in the walled discharge end and adapted to be moved into severing engagement with the closure disk, the tube having a valve opening therein adjacent its outer end and the tube portion surrounding the valve opening moving in wiping contact with the wall of the discharge end with the opening closed by said wall when the tube is at its limit of inward movement in the walled discharge end.
